(57) **CLAIM**

The ornamental design for a hat rack for truck as shown and described.

DESCRIPTION

FIG. 1 is a perspective view of a hat rack for truck showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of portion 9 shown in FIG. 1; and, FIG. 10 is an enlarged view of portion 10 shown in FIG. 2. The broken lines shown in the figures depict portions of the hat rack for truck that form no part of the claimed design.

1 Claim, 10 Drawing Sheets
